UNITED STATES PATENT OFFICE.

WILLIAM C. BUHLES, OF SAN FRANCISCO, CALIFORNIA, ASSIGNOR,
BY MESNE ASSIGNMENTS, TO HERMETIC CLOSURE CO., OF CHI-
CAGO, ILLINOIS.

APPARATUS FOR APPLYING LIQUID TO COVERS OF RECEPTACLES.

No. 823,391.

Specification of Letters Patent.

Patented June 12, 1906.

Application filed April 4, 1904. Serial No. 201,570.

To all whom it may concern:

Be it known that I, WILLIAM C. BUHLES, a citizen of the United States, residing at San Francisco, in the county of San Francisco 5 and State of California, have invented certain new and useful Improvements in Apparatus for Applying Liquid to Covers of Receptacles, of which the following is a specification.

10 My invention relates to an apparatus for applying a liquid to the covers or caps of cans, jars, and other receptacles. If, for example, liners or packing-disks are to be secured to such covers, the work can be expedited and a more satisfactory result obtained by applying the glue, mucilage, paste, or other adhesive substance to the cover itself by means of my apparatus instead of to the disk or liner by hand.

20 Besides the economy in labor, there is a great saving in material, as the adhesive liquid which is used is applied only in the exact position required and over no more surface than is absolutely necessary to give the best 25 results. Moreover, the liners being free from glue can be inserted automatically or by hand with great rapidity.

In some instances when composition packing-gaskets are associated with the covers it 30 is desirable to soften such gaskets before applying the covers to the receptacle, and this can be done by moistening them with any suitable liquid. Under some circumstances a liquid flux might be applied to such a cover 35 previous to soldering. Therefore, my apparatus is not confined to any one or more of the purposes mentioned, which have been referred to as illustrative only of different adaptions of which it is capable.

40 Embodiments of my invention are shown in the accompanying drawings, in which—

Figure 1 is a vertical section on the line $x-x$ of Fig. 2. Fig. 2 is a top plan. Fig. 3 is a vertical section of the rotary moistening head on line $y-y$ of Fig. 4. Fig. 4 is a plan of the same. Fig. 5 is a vertical section illustrating a modification of the same.

50 Any convenient frame or table 1 supports a vessel 2, which contains the liquid to be applied to the covers. A hollow foot 3 of the receptacle extends down through the table and forms a bearing for the vertical shaft 4,

having a belt-pulley 5. Power is applied to this pulley in any suitable way. I have shown a belt 6, guided by pulleys 7 8, journaled in a bracket 9. The upper end of shaft 4 extends into the receptacle and is threaded to fit the correspondingly-threaded boss 11 on the rotary head 12, which constitutes the moistening device. This head is a hollow 60 circular casting having a rim or seat 13. The wall of the casting is slightly undercut, as shown at 14, so that fine vertical passages 10 can be drilled through the rim communicating with the interior. As I prefer to leave the 65 casting open at the top and close it with an interior plate 15, I provide a shoulder 16 for such plate to rest upon, as shown. The entire casting might be formed in one piece with a closed top; but both as a matter of convenience in manufacture and in order to have ready access to the interior for cleaning, &c., I prefer to use the close-fitting top plate 15. The upper rim of the closing-plate is shown as projecting above the perforated edge of 70 the head and is rounded, and the plate itself is depressed within said rim. This is because the particular head shown in the drawings is adapted to receive a cover a of a particular shape. The cover has a central sunken 80 panel 17, a circular surrounding bead 18, a flat seat 19, and a downwardly-projecting flange 20. I do not, therefore, limit the shape of the head to the form shown, and changes required to adapt it to covers of other forms 85 are within the spirit of my invention.

An opening is made through the head to admit liquid to its interior, and I prefer to provide such opening with the projecting scoop 21. When the parts are in position, as 90 shown in Fig. 1, this scoop is immersed in the liquid. The rotation of the head causes the liquid to enter it, and the centrifugal force throws said liquid outwardly and upwardly, so that it rises through and exudes from the 95 passages 10. If a cover a be fitted and held stationary upon the rotary head, its flat seat 19 will receive the exuding liquid, which will be spread upon the whole surface of the seat by the rotary rubbing action. As fast as one 100 cover is moistened and removed another can be applied, as there is a constant feed through the passages 10.

In order to prevent the rotation of the head

from setting up a rotary rising movement of the liquid in the main vessel, I place within said vessel the annular stationary disk 22, having wings 23. The wings break up any rotary current, while the overhanging disk acts as a guard against any tendency of the liquid to rise along the wall of the main vessel.

A discharge-pipe for emptying the main vessel is shown at 24, provided with any suitable valve 25.

A modification in construction is shown in Fig. 5. The covering-plate 15 is in this case movable and guided by a central pin 26 and is held up by a spring 27, encircling said pin between the bottom of the moistening-head and the closing-plate itself. The purpose of this modification is to enable the closing-plate to act as a piston, and so to assist the centrifugal action, which causes the liquid to rise and exude through the passages 10. The operator in applying the cover presses down upon it, depressing the closing-plate, and as the hollow head is full of liquid a forcing action takes place, which may be desirable when thick liquids are employed or when for any reason the automatic centrifugal feed is not sufficiently positive.

Having thus described my invention, what I claim as new, and desire to secure by Letters Patent, is—

1. A device for moistening covers, comprising a hollow rotary head, having a seat for the cover, means for admitting a liquid to said head, and liquid-outlets through said seat.

2. A device for the described purpose, comprising a vessel for holding a liquid, a hollow rotary head, a passage for admitting the liquid to the interior of said head, a seat for the cover of a receptacle, and liquid-outlets through said seat.

3. A device for the described purpose, comprising a vessel for holding a liquid, a hollow rotary head within the same, a passage for admitting liquid to the interior of said head, a seat for the cover of a receptacle, and liquid-outlets through said seat.

4. A device for the described purpose, comprising a hollow open-topped rotary head, adapted to contain a liquid, openings in the upper edge of said head for the escape of such liquid, and a receptacle for containing said liquid in which said head rotates.

5. In a device for the described purpose, a hollow, open-topped, rotary head, a plate for closing said open top, means for admitting liquid to said hollow head, and outlets in the rim of said head for the escape of said liquid.

6. The combination with the stationary liquid-containing vessel, of a hollow head, rotary therein and having an opening for the admission of liquid, and passages formed in

the wall of said head for the escape of such liquid.

65

7. The combination with a stationary liquid-containing vessel, of a hollow rotary head having its upper end formed so as to guide and seat the cover of a receptacle, outlets for liquid at such upper end, and an opening for the admission of liquid to the interior of said head.

8. In a device for the described purpose, a liquid-containing vessel, a rotary head therein, a scoop projecting from said head and communicating with its interior, a seat for covers at the upper end of said head, and passages from the interior through said seat.

75

9. In combination with a stationary liquid-containing vessel and with a rotary head therein, wings in said vessel for preventing said head from setting up rotary currents within said vessel.

80

10. In combination with a stationary liquid-containing vessel, and with a rotary head therein, a guard-disk extending inwardly from the rim of said vessel.

85

11. In combination with a stationary liquid-containing vessel, and with a rotary head therein, a removable structure comprising a guard-disk having wings, substantially as and for the purpose set forth.

90

12. In an apparatus for the described purpose, a hollow circular rotary head having outlets for the escape of liquid, and a depressible closing plate or piston adjacent to the liquid-outlets and adapted to receive the cover of a receptacle.

95

13. In an apparatus for the described purpose, a hollow rotary head having openings for the admission and escape of liquid, a depressible closing-plate adjacent to the liquid-outlets, and a spring opposing the depression of said plate.

100

14. In an apparatus for the described purpose, a hollow rotary head having openings for the escape of liquid in combination with a depressible plate forming a seat for the cover of a receptacle, and acting, when depressed, as a piston to force liquid through said openings.

105

15. In an apparatus for the described purpose, a hollow circular rotary head having openings for the escape of liquid in combination with a depressible plate forming a seat for the cover of a receptacle, and acting, when depressed, as a piston to force liquid through said openings and a spring opposing the depression of said plate.

110

In testimony whereof I have affixed my signature, in presence of two witnesses, this 26th day of March, 1904.

WILLIAM C. BUHLES.
